UNITED STATES PATENT OFFICE

141,511

DESIGN FOR A LOUD SPEAKING TELEPHONE DESK SET

Theodore C. Riebe, Chicago, Ill., assignor to Automatic Electric Laboratories, Inc., Chicago, Ill., a corporation of Delaware

Application October 23, 1944, Serial No. 115,922

Term of patent 14 years

(Cl. D26—14)

To all whom it may concern:

Be it known that I, Theodore C. Riebe, a citizen of the United States of America, residing at Chicago, Cook County, Illinois, have invented a new, original, and ornamental Design for a Loud Speaking Telephone Desk Set, of which the following is a specification, reference being had to the accompanying drawing, forming a part thereof.

I claim:

The ornamental design for a loud speaking telephone desk set, as shown.

THEODORE C. RIEBE.
